TRAFFIC SIGNAL ADAPTOR UNIT

Walter J. Kolb, Chicago, Ill.

Application April 7, 1954, Serial No. 421,600

3 Claims. (Cl. 40—131)

This invention relates to an improvement for lighted traffic signals of the message type.

The improvement comprises an adaptor unit which can be attached to or used in conjunction with any of the known lighted traffic signals, which display a message to either pedestrians or drivers.

In the Chicago area a traffic signal section consists of one compartment of a standard three section signal head, or the one compartment as a single unit. The adaptor unit and shield of this invention may be employed with the standard three section signal head or the single unit with equal facility.

It is an object of this invention to provide an adaptor unit for a traffic signal section as presently used, which adaptor will convert the circular lens area for a message to a rectangular area so that the message will have the same uniform letter height and will also have a greatly increased width making the message more readable.

It is a special object of this invention to provide a traffic signal message unit capable of being adapted to the incandescent lighting furnished by the optical units of the already installed traffic signals to which the apparatus of this invention can be attached.

It is also a special object of this invention to provide a traffic signal message unit in which the message is written with neon illuminated tubing and in which installations the existing optical units have been removed. In such cases the plane of the neon tubing is inclined forward from the vertical to facilitate reading from an angle below the message signal.

A special feature of the apparatus of this invention is the use of reflectors at both sides of the adaptor unit to disseminate the available incandescent illumination over the entire converted message area. The reflectors are designed to spread the reflected rays of the traffic signal optical unit principally horizontally thereby widening the illuminated message.

Another special feature of this invention is the provision of a traffic signal adaptor unit in which the message bearing surface is inclined forward five degrees from the vertical, and the top surface and visor for shielding the message bearing surface is inclined downward fifteen degrees from the horizontal.

The foregoing objects and features of this invention, as well as others inherent in the apparatus of this invention, will be readily apparent from the following specifications and description of the accompanying drawings wherein like reference characters designate corresponding parts in the several views.

Figure 1 is a front view of the broader message bearing signal with the adaptor unit and shield in place and the actual lens area indicated by dotted outline.

Figure 2 is a side view of the adaptor unit and shield attached to the front door of a standard housing for such a traffic signal.

Figure 3 is a top view of the same showing the sleeve of the adaptor unit press fitted into and adaptor collar

2

which holds the standard lens in the door of the standard housing.

Figure 4 is an enlarged sectional view of a portion of the adaptor unit which shows the reflector in place in the right side of the adaptor unit, being along line 4—4 of Figure 1.

Figure 5 is an enlarged vertical sectional view of the adaptor unit and shield along line 5—5 of Figure 1, which shows the use of neon lighted tubing to spell the message signal, which eliminates the use of lettering on the front glass or a mask in front of or behind said front glass, and also permits removal of the optical lighting unit from the existing traffic signal installation.

Figure 6 is a fragmentary view of one reflector.

Referring to the drawings Figure 1 gives the typical result of looking at a lighted message bearing the signal which has the adaptor unit and shield or hood attached to a standard traffic signal installation using incandescent illumination. The top of the adaptor is indicated by numeral 6, the shield or hood by 7, and the bottom of the adaptor by 8. The dotted circle 9 indicates the lens frame of the traffic signal unit and the dotted vertical lines 10 and 11 outline the back ends of the side wings 10a and 11a respectively of the adaptor unit. The message "Walk" is illustrated enlarged beyond the lens area because by reason of the reflectors installed on the side wings of the adaptor unit the message area actually is broadened approximately on a scale as illustrated.

The side view of Figure 2 shows the optical unit compartment 12 with a hinged door 13 to the compartment of a standard traffic signal. The circular sleeve of the adaptor unit is slip fitted or pressed into the adaptor collar 15 which holds the lens 13a of the optical unit compartment 12. The same connection of the adaptor unit to the adaptor collar 15 is shown in Figure 3 except that it is a top view, revealing the rectangular shape of the top of the shield or hood 7 and the irregular shape of the top 6 of the adaptor unit. The use of a shield or hood 7 in conjunction with the adaptor is important because it shuts off the direct rays of the sun in the early morning or late afternoon when the message bearing signal is faced into the sun. For added protection of the observer of the signal the hood dips downward fifteen degrees from the horizontal in the same continuous plane as the top surface 6 of the adaptor. For the same advantage side shields 16 are provided so that direct light striking the front of the adaptor will not depreciate or lessen the advantages of the adaptor unit of this invention.

The horizontal sectional view of Figure 4 taken along line 4—4 in Figure 1 shows the circular sleeve 14 on the back of the adaptor unit pressed or slip fitted into the adaptor collar 15 which is held in turn by the hinged door 13 to the compartment 12. In practice the lens 13a to the optical unit compartment is first removed from door 13 and the adaptor collar 15 inserted in the door after which the lens is replaced. The sleeve 14 has bayonet bolts 20 spaced around its outside surface which slide into the slots 21 when the sleeve is pressed or slip fitted into the adaptor collar 15. A slight turn of the circular sleeve 14 inside the adaptor collar 15, or preferably a slight turn of collar 15 around sleeve 14 will move the slot into locking position and fasten the adaptor unit to the door of the traffic signal unit. The method of attachment would be the same if the traffic signal unit had a single or multiple optical unit compartment.

Figure 4 also shows one of the reflectors 17 in the side of the adaptor unit and a glass window 18 as the front face of the unit. Normally there would be two similar reflecting surfaces 17 in the adaptor unit, one on each side of the opening in the back wall of the adaptor. The message of the converted traffic signal unit will be either a lettered glass window, or a mask to fit behind a

clear glass window 18. It is also within the scope of this invention to use a clear plastic window, for example, one made out of Lucite, etc.

When it is desired to use neon tubing to signal a message the incandescent optical unit is removed from compartment 12 and reflector 17 are removed from the adaptor unit, but a panel 19 of neon tubing is disposed in the adaptor unit parallel to glass window 18 as shown in Figure 5. In such cases the glass window 18 is clear and primarily protects the tubing from the weather.

Figure 6 is a front view of the reflector on the right side of the adaptor unit when looking toward it with the dipping top surface 6 and turned up bottom surface 8 and inclined shield 7 removed. The reflecting surface 17 is shown as conically shaped around the lens opening that is outlined by circular sleeve 14. Any of the usual materials for reflecting light, such as mirrors, highly polished metal, foil, etc., may be used in constructing reflectors for use in the adaptor unit. It is an obvious advantage to have the reflecting surfaces deepest at the points where the conical surfaces are attached to the sides 10a and 11a of the adaptor unit so as to obtain maximum reflection of light horizontally in order to widen the message.

It should be apparent after reading the foregoing description of the elements and features of the adaptor unit and shield that it is first of all simple of construction. Secondly it is a very useful invention, and thirdly, in view of the present status of signaling traffic messages, it is most practical. For example, it is a device that may be applied to all section traffic signals now installed or being manufactured. Also, it may be applied to a traffic signal section consisting of one compartment of a standard three section signal head or to one compartment as a unit by itself. And lastly, should it become desirable for any reason to change from incandescent illumination to neon illuminated tubing the optical unit of the traffic signal may be removed from the installation, or merely disconnected from an electrical source as desired, and the neon illuminated tubing message inserted as a panel in said adaptor unit parallel to the front glass window with suitable transformers, relays and switches either in the place of the optical unit or in the adaptor unit.

Aside from the many applications of the device of this invention perhaps the greatest advantage of its use is the large increase in the size of the message bearing area contrasted to message signals in use today. For example, existing traffic signal installations have a circular lens area with an inside diameter of 7½ inches. By use of the adaptor unit of this invention attached to the same lens the message area has actually been converted to a rectangular area measuring 6 inches high and 11 inches wide. The message area beforehand was circular which wastes lighted area above and below a short word that has to be proportionate in size and fit within the limits of the inside diameter of the lens.

Another example to prove the value of this invention is a four letter word like Walk when lettered on a lens of the present standard traffic signal installations, or when a mask in front of or behind the lens is used, the letters cannot exceed 2 inches in height. By use of the adaptor unit of this invention it is possible to use a lettered glass panel 18, or with a mask behind a clear glass window converts the message bearing area beyond all expectations 18, using letters 5 inches high proportionately spaced on a glass area 6 inches high and 11 inches wide.

The improvement made possible by the use of reflectors where incandescent illumination is used. And the attaching of the adaptor unit to existing installations that are converted over to the use of neon illuminated tubing

permits the use of neon tube lettering as high as 4 inches because of the larger lighted window glass 18.

The window or lettered glass 18 is tipped forward 5 degrees from a vertical position in order that dust and dirt will be less apt to cling to the outside surface of the glass, and also to put the message bearing surface more directly into line of vision of the pedestrian and motorist who normally are below the traffic signals.

The top surface of the adaptor unit and the attached shield are inclined down 15 degrees from a horizontal position so as to shield the message bearing area from the sun's rays when in line with the traffic signal, and also to more readily shed water and snow.

What I claim is:

15 1. A traffic signal adaptor unit comprising a housing having six defining surfaces none of which are parallel, the two side surfaces angling outwardly from the back of said housing, the top surface inclining downwardly while the bottom surface inclines upwardly from the back to the front of said housing, the back surface having a circular opening which is fitted with a circular sleeve projecting rearwardly for attaching said adaptor to a source of light, the front surface being of transparent material and tipped forward slightly between the said

20 down turned top surface and up turned bottom surface, which inclination of said top and bottom surfaces intensifies the light directed upon said front surface, and said front surface having opaque lettering thereon.

25 2. An adaptor unit with means for attachment to an external source of light comprising a housing having a rear wall with a central circular opening therein, diverging side walls, converging top and bottom surfaces and a translucent front surface having opaque lettering thereon, said rear wall having a circular sleeve protruding rearward from said central circular opening, a circular adaptor collar capable of receiving said circular sleeve in close engagement, said adaptor collar having suitable means for attaching said housing to said source of light, and a conically shaped reflecting surface attached to each side of said central circular opening within said

40 housing.

30 3. An adaptor unit with means for attachment to an external source of light comprising a housing having a rear wall with a central circular opening therein, diverging side walls, converging top and bottom surfaces and a translucent front surface having opaque lettering thereon, said rear wall having a circular sleeve protruding rearward from said central circular opening, a circular adaptor collar capable of receiving said circular sleeve in close engagement, said adaptor collar having suitable means for attaching said housing to said source of light, and a conically shaped reflecting surface attached to each side of said central circular opening within said

45 housing, each of said reflecting surfaces extending diver-

50 gently forward to meet said translucent front surface.
